UNITED STATES PATENT OFFICE.

GRANT HAMMOND, OF HARTFORD, CONNECTICUT, ASSIGNOR TO THE DALTON ARMS CORPORATION, OF NEW YORK, N. Y., A CORPORATION OF NEW YORK.

FIREARM.

1,294,454.

Specification of Letters Patent. Patented Feb. 18, 1919.

Application filed April 21, 1916. Serial No. 92,780.

To all whom it may concern:

Be it known that I, GRANT HAMMOND, a citizen of the United States, and a resident of Hartford, in the county of Hartford and State of Connecticut, have invented a new and Improved Firearm, of which the following is a specification.

My invention relates more especially to that class of magazine firearms that are discharged while supported by a person and in which there is a manually actuated breech-bolt, and an object of my invention, among others, is to provide a firearm of this type that shall be simple in its construction and particularly effectual in its operation.

One form of device embodying my invention, and in the construction and use of which the objects herein set out, as well as others, may be attained, is illustrated in the accompanying drawings, in which—

Figure 1 is a view in vertical longitudinal section of that portion of a firearm embodying my invention, the magazine and breech-bolt being shown in full.

Fig. 2 is a view in side elevation of a portion of my improved firearm with the receiver broken away to show the interrupter.

Fig. 3 is a view in cross section on plane denoted by dotted line 3—3 of Fig. 2.

Fig. 4 is a top plan view of a portion of my improved firearm.

Fig. 5 is a view in cross section on plane denoted by dotted line 5—5 of Fig. 2.

Fig. 6 is a bottom view of the breech-bolt, and firing mechanism, with the parts in the relative position occupied when the bolt is closed in the receiver, the firing mechanism being uncocked.

Fig. 7 is a side view of the breech-bolt, looking toward the left.

Fig. 8 is a view in cross section on plane denoted by dotted line 8—8 of Fig. 7.

Fig. 9 is a view in section lengthwise through the breech-bolt and firing mechanism.

Fig. 10 is a top plan view of the breech-bolt in the position occupied when closed.

Fig. 11 is a view looking toward the forward end of the breech-bolt.

50 Figs. 12 and 13 are detail views showing the construction of the extractor.

Figs. 14 and 15 are detail views of the compression sleeve.

Fig. 16 is a bottom view of the stop piece.

Fig. 17 is an end view of the firing pin head, the firing pin being removed.

In the accompanying drawings the numeral 10 indicates the receiver of my improved firearm, 11 the barrel secured thereto in any ordinary manner and 12 the magazine 60 preferably separately formed from the receiver and including a trigger guard plate with a trigger guard 13. The magazine may be of any desired form, its special construction not being material to the invention 65 of this application, and it may be attached to the receiver, stock, etc., in any desired manner. A trigger 14 is pivotally mounted in the receiver, its lower end projecting through an opening into the trigger guard 70 and its upper end projecting through an opening in the receiver in position to form a breech-bolt stop, said trigger being also connected to operate a movable sear 15, all in a manner to be hereinafter described.

The receiver 10 has a breech bolt chamber 16 of generally round form in cross section and with breech bolt locking shoulders 17 at its forward end and a breech bolt releasing 80 groove 18 extending from said shoulders backwardly into the main part of said chamber, a spline groove 42 extending along the bottom of said chamber for its full length. This chamber 16 has an opening 19 through 85 its wall into the magazine through which cartridges pass into the chamber, and the empty shells are ejected through a discharge opening in the top and side of the receiver in a manner common to firearms of this class. The chamber 16 extends out at the rear end of the receiver, and a guide slot 20 opens through the top of the receiver from the rear end of this chamber. Loading slots 21 are 90 located in the side walls of the slot 20 to receive the lower end of a loading clip containing cartridges, to hold said clip while the cartridges are forced out from its lower end through the breech bolt chamber and into the magazine while the breech bolt is 95 held in its rearward position.

A breech bolt 22 is formed to fit within the

breech bolt chamber 16 and is provided with breech bolt locking lugs 23 shaped to pass through the releasing groove 18 and spline groove 42 and to engage the locking shoulders 17 and hold the breech bolt in its closed position when it has been rotated to lock it in place.

A locking rib 24 of a length to fit between the front and rear edges 25-26 of the discharge opening, projects from the side of the breech bolt and in line with one of the locking lugs 23, a slight space being left between the forward end of the rib and the lug. The front and rear ends of the rib 24 are beveled. The beveled rear end of the rib engaging the edge 26 cams the breech bolt forward and aids in holding the breech bolt in its locked position and the engagement of the front end of said rib with the inclined part 63 of the edge 25 of the discharge opening forces the breech bolt backwardly as it is rotated to its open position and thus loosens the cartridge shell by reason of the hold of the extractor 27 thereon. This extractor is located in an extractor groove 28, the back end of which is slightly narrower than the front end and with its edges undercut to receive the dovetail shaped end 29 of the extractor. An opening 30 in the groove 28 receives a lug 31 projecting from the back of the extractor. The extractor is resilient so that it may be sprung sufficiently to permit the lug to enter the opening, the lug being of such length that it will not be drawn out of the opening when the extractor lip rides over the cartridge flange. When said lip has engaged said flange and the bolt is moved backward the pull exerted to extract the cartridge shell is sustained by said lug within said opening. A firing pin opening 32 of different diameters in cross section to receive a similarly shaped firing pin 33 extends through the breech bolt from end to end, the rear end of this opening being of the greatest diameter and the front end being comparatively small to receive the firing tip of the firing pin. A main or firing spring 34, of spiral form, is located upon the firing pin and is placed under compression by a compression sleeve 35 through which the rear end of the firing pin extends. Before these parts are secured within the breech bolt the sleeve is held to compress the spring by means of a cocking head 36 with an opening lengthwise therethrough, the forward end of which opening is threaded to fit a thread 37 located at a distance from the rear end of the firing pin. The compression sleeve has a thread 38 to fit a thread 39 upon the interior of the breech bolt, the sleeve being thus secured to hold the main spring under compression when the parts are assembled within the breech bolt, and the force of the spring being then exerted to force the firing pin and

cocking head forward within the breech bolt. A slot 40 is formed through the wall of the sleeve on its under side to receive a projection 43 from the underside of the cocking head, within which slot said projection moves during the operation of the firing pin. A notched shoulder 41 at the mouth of this slot receives a retaining and firing pin locking lug 46 located at the front end and at one side of the projection 43. This is for the purpose of holding the cocking head in a retracted position while the sleeve 35 is being screwed into the breech bolt, and also for locking the firing pin to the breech bolt. The front end of the projection 43 is formed with a lug 46 and a cocking lug 44, the latter being located on the opposite side of the projection 43 from the lug 46 and in position to engage a notched shoulder 45 on the breech bolt 22 to hold the firing pin in its cocked position during the reciprocating movement of the breech bolt. The lug 46 is of a depth to project through the compression sleeve and engage a safety locking notch 47 in the extreme end of the breech bolt to lock the firing pin and bolt together to prevent unintentional action. A safety lug 49 extends from the front end of the projection 43 on the side opposite the locking lug 46 and at a distance from the body of the cocking head greater than that of said lug 46 and in position to engage the side of the spline groove 42, the corner formed by said groove and the circular wall being received within a safety groove 70 in the bottom of the projection 43, thus locking the breech bolt and firing pin against relative turning movement. A slot 51 is cut through the wall of the breech bolt at the rear end thereof, one edge of this slot being spirally formed to constitute a cocking cam 50, that engages the front end of the projection 43 on the cocking head to move the firing pin backwardly and cock it as the breech bolt is turned to its open position by means of a handle 52 that projects from the rib 24 and that may be integral therewith or otherwise as may be desired. The cocking cam 50 terminates at its rear end in the notched cocking shoulder 45 hereinbefore described.

An interrupter groove 53 extends along the breech bolt in position to receive an interrupter lug 54 from the side of an interrupter 55 secured to the receiver and having a finger 56 adapted to pass through an opening in the side wall of the magazine and engage the cartridges therein to regulate their delivery into the magazine chamber. This interrupter is composed of metal having spring qualities and an interrupter cam 57 is formed at one end of the groove 53 for the purpose of effecting and controlling the operations of the interrupter to cause it to properly perform its functions.

A groove 58 having its side walls undercut extends partially around the breech bolt from the groove 53. Openings 59 are cut through the lips of this dove-tailed shaped 5 groove to receive one side 60 of a two part lug projecting from the under side of a stop piece 61 that limits backward movement of the breech bolt. The other part 62 of said lug is received in the groove 53, the points 0 64 on the breech bolt between the openings 59 and groove 53 being located in the space 65 between the parts 60 and 62 of the lug. The two part lug is beveled at its opposite 5 ends to fit the undercut edges of the dove-tail shaped groove 58 and when the stop device is in the position above described it may be slid to one side and located within the groove.

A trigger spring 71 extends through an 10 opening in the trigger to hold it in one position and a lug on the end of this spring constitutes the sear 15, to engage a cocking shoulder 73 on the projection 43 on the cocking head.

25 A stop groove 66 extends along the outer surface of the stop piece, the front wall of the groove being adapted to engage the upper end of the trigger 14 that thus acts as a stop to the backward movement of 30 the breech-bolt. By pressing the trigger backwardly to its full extent its upper end will be so moved that it may be disengaged from the end wall of the stop groove and the breech-bolt may be removed from its 35 chamber in the receiver. The rearward end of the stop groove is beveled off as at 67 so that it will freely pass the rims of the cartridge shells in the backward movements of the breech-bolt.

40 To assemble the firing pin, cocking head and compression sleeve, the sleeve is slipped over the body of the cocking head, the main spring is placed upon the firing pin, and the latter is passed through said sleeve and 45 into the opening in the cocking head. The parts are forced together, slightly compressing the spring, and the thread on the firing pin is engaged with that in the opening in the cocking head and screwed to place.

50 To assemble these parts in the breech-bolt the compression sleeve is forced toward the firing tip of the pin tensioning the main spring until the shoulder 41 is opposite the lug 46 when the sleeve is turned to engage 55 said lug with the notch in said shoulder. The parts are now inserted in the breech-bolt, the sleeve holding the cocking head with its projection 43 away from the end of the breech-bolt when the thread 38 first engages 60 the thread within the breech-bolt. The parts are screwed to place by force applied to the cocking head, and just before the threads are seated the forward part of the projection 43 encounters the end of the 65 breech-bolt and the sleeve 35 being screwed

farther inward, the lug 46 is disengaged from the notch 41, the cocking head is turned, and the lug 43 moves into the slot 40 in the compression sleeve and under the force of the main spring 34. 70

To assemble the bolt in the receiver the cocking head is pulled backwardly up the cocking cam and is turned to engage the cocking lug 44 with the cocking shoulder 45. The stop piece 61 is alined with the 75 bottom lug 23 on the breech bolt and the latter may then be pushed into the chamber in the receiver, the handle 52 passing through the slot in the top of the receiver. When the breech bolt is pushed fully inward the handle 52 is turned downwardly to lock the parts in place. 80

By pulling the cocking head outwardly and turning it until the locking lug 46 engages the safety locking notch 47 in the 85 breech bolt the safety lug 49 will be engaged within the side of the spline groove 42 and in this position of the parts the corner 48 at the mouth of said groove is located in the safety groove 70 and the firing pin is 90 held against forward movement and the breech bolt against turning movement so that it cannot be unlocked. Also in this position of the parts the lug 49, resting 95 against the side of the spline groove, prevents the handle 52 from being raised to unlock the breech-bolt, as the latter is locked to the firing head and the engagement of the lug 43 with the end of the receiver prevents inward movement of the firing pin. 100

While I have shown and described herein a construction of parts that satisfactorily embodies my ideas, this may be departed from to a greater or lesser degree and yet be within the spirit and intent of the 105 invention.

I claim:

1. A rotatable breech bolt for a gun, said bolt having locking lugs thereon and a stop bar attached to the bolt to register in line 110 with one of the lugs of the bolt, means for preventing turning movement of the stop bar when said bolt is turned to its unlocked position, and means for attaching the stop bar to the bolt. 115

2. A breech bolt for a gun, said bolt having a peripheral groove with overhanging walls running part way around its circumference, a stop bar having a projecting lug with overhanging lips and of approximately 120 the same width as the peripheral slot in the bolt to removably attach it to the bolt, the lug operating in the peripheral slot to permit turning movement of the bolt independently of said stop bar. 125

3. A breech bolt for a gun, said bolt having a peripheral groove with overhanging lips and with openings cut through said lips, and a member movably mounted on the breech bolt and having a lug to pass through 130

- said openings for attaching purposes, and ends underlying said lips.
4. A breech bolt for a gun, said bolt having a peripheral groove with overhanging lips and with openings cut through said lips, said bolt also having a longitudinal groove, and a member movably mounted on the breech bolt and having a divided lug to fit into said openings and groove for attaching purposes and ends to underlie said lips.
5. A breech bolt for a gun having a peripheral groove with overhanging walls running part way around its circumference, a stop bar having a concave and a convex side 10 with a projecting concave lug with overhanging lips projecting from its concave surface, the lug being of approximately the same width as the peripheral slot in the bolt, the lug operating in the peripheral slot to 15 turn part of the distance around the circumference of the bolt.
6. A breech bolt for a gun, said bolt having locking lugs, a rib and a handle mounted on one side, a cocking cam and notch at its 20 rear end, a sleeve in the bore of the rear end, said sleeve having a ledge formed in its rear wall and a longitudinal slot through its bore, a firing pin rod passing through the forward part of the sleeve, a cocking 25 head mounted in the rear of the sleeve and means for attaching the firing pin rod to the cocking head.
7. A receiver, a breech bolt located in the receiver, a cocking head having a projection 30 with a bifurcated lug shaped to lie flush with the outer surface of the breech bolt, said projection having a transverse step forming a shoulder located backwardly of the bifurcated end, and a sear mounted in 35 the receiver to engage said shoulder.
8. A cocking head for a breech bolt, said head having a projection from its under surface bifurcated at its forward end to form two lugs and a third lug extending from 40 the forward end of said projection back of the bifurcated part and at a greater distance from the axis of the head.
9. A cocking head for a breech bolt, said head having a projection from its surface 45 and with its forward end bifurcated to form two lugs, a transverse step having a shoulder located rearwardly of the bifurcated end, and a lug extending from one side of 50 said shoulder.
10. A cocking head for a breech bolt, said head having a lug projecting from its surface, the forward part of the lug being bifurcated and of a diameter equal to that of the bolt in which the cocking head operates, a transverse step formed slightly to the rearward of the bifurcated end, the step extending part way across the face of the bottom of 55 the lug, and a lug projecting forward of the step.
11. A breech bolt for a gun, said bolt having locking lugs, a rib, a handle removably secured thereto, a movable stop bar attached to the forward end of the bolt, a spiral cam cut in the rear end of said breech bolt, said cam extending to a ledge formed 60 near the end of the bolt, that part of the ledge adjacent the wall of the spiral cam projecting past the inner part of the ledge.
12. A breech bolt for a gun, said bolt having a compression sleeve secured within 65 its rear end, a firing pin located in the breech bolt and extending through said sleeve, a cocking head secured to the firing pin, a projection from said cocking head, means for locking the cocking head and 70 sleeve together to hold said projection in a retracted position for engagement of said sleeve with said breech bolt and means for disengaging said parts as the sleeve is turned to its seat.
13. A breech bolt for a gun, said bolt having a notch in its end, a compression sleeve located in said bolt, means for securing the sleeve to the bolt, a firing pin located 75 in the breech bolt and extending through said sleeve, a cocking head secured to the firing pin, a projection on the cocking head adapted to lock it to said sleeve and also to 80 engage the notch in the breech bolt to lock said head to the breech bolt and means for disengaging said parts as the sleeve is turned to its seat.

GRANT HAMMOND.
